UNITED STATES PATENT OFFICE

2,234,000

DISPLAY STAND

Landon C. Galton, Canajoharie, N. Y., assignor to
 Beech-Nut Packing Company, Canajoharie,
 N. Y., a corporation of New York

Application December 24, 1937, Serial No. 181,624

2 Claims. (Cl. 248—196)

The present invention relates to display stands, and has special reference to display stands for supporting open top boxes or cartons containing packages of candies, chewing gum, or other small packages on the counter for the purpose of displaying the contents thereof.

One of the objects of the present invention is to provide a display stand of the character indicated which is simple in construction, attractive 10 in appearance and convenient in use, and which displays the carton and its contents to the best advantage.

Another of the objects of the invention is to provide a display stand of this character having 15 a coin receptacle of novel and improved construction.

In the accompanying drawing,

Figure 1 is a view in perspective of a display stand embodying the features of my invention 20 in their preferred form, an open top box or carton adapted to contain small packages being shown by dot and dash lines in position on the stand;

Fig. 2 is a longitudinal sectional view taken 25 substantially on the line 2—2 of Fig. 1, the carton being shown in section; and

Fig. 3 is a sectional plan view taken substantially on the line 3—3 of Fig. 2, but with the carton removed.

The display stand as illustrated in the drawing, is particularly adapted for displaying an open top box or carton 2 which may contain 30 small penny packages of candies, chewing gum, or other small packages, on the counter of a store. The carton may be made of pasteboard of the usual form having a fly-leaf 3.

As shown the stand comprises a support 4 and a platform 6. The support 4 may be attractively made of sheet metal and comprises a 40 member having a vertical wall 8, rearwardly bent side wings or walls 10 and a channel shaped forward portion at the lower end of the vertical wall having a forwardly extending bottom wall 12 and an upwardly turned wall 14 at the forward 45 edge of the bottom wall 12, the walls 8, 10, 12 and 14 being preferably formed of a single piece of sheet metal. The bottom channel wall 12 and the lower end edges of the side walls 10 are substantially in the same plane so as to provide a 50 stable supporting surface for the stand.

The upper edge of the vertical wall 8 is turned over to form a downwardly opening channel or groove 16. The vertical wall 8 also has two forwardly struck ears or lugs 18.

The platform 6 may be made of a wire which

is bent into U-form and has the ends of its legs bent inwardly and pivotally mounted in apertures in the lugs 18. The forward end portion of the platform 6 has a downwardly bent portion 20.

When the display stand is not in use, and for shipping purposes, the platform 6 may be swung upwardly against the vertical wall 8 as indicated by broken lines in Fig. 2.

When in use, the platform 6 is swung down 10 into the position shown in full lines in Figs. 1 and 2, the forward downwardly turned end 20 of the platform resting on the counter and the upper edge of the channel wall 14 serving as a stop or rest for the platform when the display 15 stand is lifted from the counter.

The carton 2 containing packages (not shown) may be placed on the platform with its rear edge portion resting on the top of the lugs 18 and the upper edge of the fly-leaf 3 inserted into the 20 tightly fitting groove 16. The edge of the fly-leaf is firmly held in the groove 16 by the engagement of the bottom of the carton with the lugs 18. Thus the carton may be easily removed and replaced on the platform 6.

Viewing the stand from the front, when the carton is in position on the stand, only the portion of the stand support above the upper edge of the fly-leaf of the carton is visible, and the packages in the inclined carton are displayed to 30 the best advantage and may be conveniently removed by the customer.

As shown, the stand is provided with a coin receptacle at the rear thereof into which the customer may deposit a penny or other coin upon 35 removing a package from the carton.

This coin receptacle has a rear wall 20 and side walls 22 formed from a single piece of sheet metal. The inner edges of the side walls are turned outwardly to form flanges that are secured by rivets 24 to the vertical wall 8. The upper edges of the side walls 22 are inclined upwardly from the upper edge of the wall 8, and the rear wall is extended upwardly above the wall 8 and may have printed matter thereon.

A coin release member 25 of sheet metal is pivotally mounted in the coin receptacle. This member has a vertical portion 26, the lower portion of which is curved downwardly and rearwardly to form a rearwardly extending portion 50 28. The outer end of the portion 28 projects beyond the rear wall 20 of the receptacle. The vertical edges of the portion 26 has outward projections 30 which are pivoted in apertures in the side walls 22 of the receptacle.

Normally the coin release member 25 is held in the full line position shown in Fig. 2. In this position the portion 28 thereof closes the opening at the lower end of the rear wall 20, the portion 28 5 engaging the lower edge of the rear wall 20. The coin release member 25 is held in this position by the engagement of the longitudinal edges of the portion 28 thereof with inwardly pressed protuberances 32 in the side walls 22 of the receptacle.

When the coin release member is in the described position, upon a coin being deposited in the coin receptacle it drops down upon the portion 28 and rests thereupon. When the store- 15 keeper desires to examine the coins deposited, or to empty the coin receptacle, he presses downwardly on the rear end of the horizontal portion 28 so as to force that portion downwardly over the protuberances 32 and into the position 20 shown by dotted lines in Fig. 2, the upper end of the coin release member engaging the forward side of the rear wall of the receptacle. When the coin release member is thus operated, the coins slide out from the receptacle and may be caught 25 in the hand of the storekeeper. In case further coins are placed in the receptacle while the coin release member is in the discharge position, the coins will pass down through the opening provided between the release member and the vertical wall 8 of the stand.

As will be evident to those skilled in the art, my invention permits various modifications without departing from the spirit thereof or the scope of the appended claims.

What I claim is:

1. In a display stand of the class described, a support formed of sheet metal having a front wall, side walls extending rearwardly from the front wall, and a bottom wall extending forwardly from the front wall and having an upstanding flange spaced a distance from the front wall, said stand adapted to be positioned on a store-counter with said bottom wall and the lower ends of said side walls resting on the counter so as to provide stable supporting means for the stand, and a platform hingedly connected to the front wall of said support and its forward end resting on the counter when the stand is in use, said platform adapted to engage the upper edge 15 of said flange when the stand is lifted so as to limit the downward swinging movement of the platform.

2. In a display stand of the class described, a support formed of sheet metal having a front 20 wall, side walls extending rearwardly from the front wall, and a bottom wall extending forwardly from the front wall, said stand adapted to be positioned on a store-counter with said bottom wall and the lower ends of said side walls resting 25 on the counter so as to provide stable supporting means for the stand, and a platform hingedly connected to the front wall of said support and its forward end resting on the counter when the stand is in use, said support having means for 30 limiting the downward swinging movement of the platform when the stand is lifted from the counter.

LANDON C. GALTON.
